DESIGN FOR A HANGING LAMP.

SPECIFICATION forming part of Design No. 14,407, dated November 13, 1883.

Application filed July 2, 1883. Term of patent 7 years.

WOLCOTT A. HULL.

Witnesses:

EDMUND A. PARKER,
C. G. STEVENS.

UNITED STATES PATENT OFFICE.

WOLCOTT A. HULL, OF NEW YORK, N. Y., ASSIGNOR OF ONE-HALF TO THE ANSONIA BRASS AND COPPER COMPANY, OF SAME PLACE.

DESIGN FOR A HANGING LAMP.

SPECIFICATION forming part of Design No. 14,407, dated November 13, 1883.

Application filed July 2, 1883. Term of patent 7 years.

To all whom it may concern:

Be it known that I, WOLCOTT A. HULL, of New York, in the county and State of New York, have invented and originated a new

5 Design for a Hanging Lamp, of which the following is a specification.

My design relates to the "harp" or frame in which the reservoir of a hanging lamp is arranged.

10 The accompanying engraving is a perspective view of a lamp embodying my design.

The lower portion of the frame consists of two curved band-like portions, *a*, which converge toward the ends, and intermediate connecting scrolls, *b*. At the center is a cruciform figure, *c*, bearing a resemblance to a four-leaved clover. Below this cruciform figure is a hand-piece, *d*, mainly of angular form, but having circular terminal portions *e*, ornamented with rosettes, and an intermediate arched-lower portion, *f*. The side portions of the harp or frame are made in the form of twisted bands *g* and scrolls *h*, extending beyond the same. Within the lower portion of the scrolls are figures *i*, bearing resemblance to sunflowers.

25 What I claim as my design, and desire to secure by Letters Patent, is—

1. A design for a harp or frame for a hanging

lamp, having a lower part composed of band-like portions *a*, intermediate scrolls, *b*, and a cruciform figure, *c*, substantially as shown and described. 30

2. A design for a harp or frame for a hanging lamp, having at the lower portion a hand-piece, *d*, made mainly of angular form, but with circular terminal portions *e*, ornamented with rosettes, substantially as shown and described. 35

3. A design for a harp or frame for a hanging lamp, having side portions, *g*, representing twisted bands, substantially as shown and described. 40

4. A design for a harp or frame for a hanging lamp, having side portions representing twisted bands *g* and scrolls *h*, extending beyond the same, substantially as shown and described. 45

5. A design for a harp or frame for a hanging lamp, having side portions, *g*, representing twisted bands, and having scrolls *h* and figures *i*, bearing resemblance to sunflowers, substantially as shown and described. 50

WOLCOTT A. HULL.
